Primary Examiner—Freda S. Nunn

(57) **CLAIM**

The ornamental design for a computer having a pull-tab, as shown and described.

DESCRIPTION

FIG. 1 is a partial perspective view of the design for the computer having a pull-tab in an inserted position, wherein the pull-tab extends substantially inwardly into the chassis of the computer;

FIG. 2 is a partial perspective view of the design for the computer having a pull-tab as illustrated in FIG. 1, wherein the pull-tab is in a pulled-out position that extends substantially outwardly from the chassis of the computer;

FIG. 3 is a front elevational view of the design for the computer having a pull-tab as illustrated in FIGS. 1 and 2; FIG. 4 is a top elevational view of the design for the computer having a pull-tab in the pulled-out position as illustrated in FIG. 2; and,

FIG. 5 is a right side elevational view of the design for the computer having a pulled-tab in the pull-out position as illustrated in FIGS. 2 and 4, the left side being substantially the same as the illustrated right side.

In these drawings, the solid lines illustrate the claimed ornamental design, whereas the broken lines illustrate environmental features that form no part of the claimed ornamental design.

1 Claim, 4 Drawing Sheets
